UNITED STATES PATENT OFFICE.

BERT L. VAN ORMAN, OF HIGHLAND PARK, MICHIGAN, ASSIGNOR TO L. A. YOUNG INDUSTRIES, INC., OF DETROIT, MICHIGAN.

WIRE-SPRING-BALING MACHINE.

Application filed November 21, 1923. Serial No. 676,072.

To all whom it may concern:

Be it known that I, BERT L. VAN ORMAN, a citizen of the United States, residing at Highland Park, county of Wayne, State of Michigan, have invented certain new and useful Improvements in Wire-Spring-Baling Machines, of which the following is a specification.

This invention relates to improvements in wire spring baling machines.

My present improvements are designed by me as part of or for use in connection with the spring forming mechanism shown in my application for Letters Patent filed June 2, 1921, Serial No. 474,399, and I have illustrated the same in the accompanying drawings as developed for use with such spring forming machine. My improvements are, however, desirable and readily adapted for use in other relations.

The main object of this invention is to provide an improved baling mechanism for wire springs by means of which they are automatically taken from the spring forming machine and packed or assembled into a compact bale and tied into such bale.

A further object is to provide an improved machine of the character described which effectively handles springs of the double helical coiled type without danger of clogging.

Further objects, and objects relating to structural details, will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing, forming a part of this application, in which:

Fig. 1, Sheet 1, is an elevation of the parts of a structure particularly relating to features of the invention.

Fig. 2, Sheet 2, is a detail top plan view.

Fig. 3, Sheet 3, is a detail elevation taken from the left of Fig. 1.

Fig. 4, Sheet 3, is a detail elevation from the left of Fig. 3, with the parts in another position or stage of operation.

Fig. 5, Sheet 4, is a view in section on a

line corresponding to line 5—5 of Fig. 2 with the parts in the same position as shown in Fig. 3.

Fig. 6, Sheet 5, is an enlarged detail view in section on a line corresponding to line 6—6 of Fig. 1.

Fig. 7, Sheet 6, is an enlarged detail view in section on a line corresponding to line 7—7 of Fig. 1.

Fig. 8, Sheet 7, is an enlarged detail view in section on a line corresponding to line 8—8 of Fig. 1.

Fig. 9, Sheet 8, is an enlarged view in section on a line corresponding to line 9—9 of Fig. 2, illustrating details of a spring transfer member.

Fig. 10, Sheet 8, is an enlarged view in section on a line corresponding to line 10—10 of Fig. 2, illustrating further transfer member details.

Fig. 36, Sheet 14, is an enlarged view in section on a line corresponding to line 36—36 of Fig. 7, illustrating details of balancing wire feed mechanism.

Fig. 37, Sheet 15, is a view in section on a line corresponding to line 37—37 of Fig. 36, illustrating further wire feed details and wire cut-off mechanism.

Fig. 38, Sheet 16, is a view in section on a line corresponding to line 38—38 of Fig. 36.

Fig. 39, Sheet 15, is a view in section on a line corresponding to line 39—39 of Fig. 38.

Fig. 40, Sheet 6, is an enlarged view in section on a line corresponding to line 40—40 of Fig. 1, illustrating further details of the wire cut-off mechanism.

Fig. 41, Sheet 14, is a detail view in section on a line corresponding to line 41—41 of Fig. 40.

Fig. 42, Sheet 14, is an enlarged view in section on a line corresponding to line 42—42 of Fig. 40.

Fig. 43, Sheet 14, is an enlarged view in section on a line corresponding to line 43—43 of Fig. 40.

Fig. 44, Sheet 16, is an enlarged view in section on a line corresponding to line 44 of Fig. 7, illustrating details of means for moving wire tying mechanism to and from 75 tying position.

Fig. 45, Sheet 16, is a view similar to a part of Fig. 40 showing the cut-off mechanism in actuated position.

Fig. 46, Sheet 17, is an enlarged view 80 taken on a line corresponding to line 46—46 of Fig. 1, illustrating details of one baling chute section.

Fig. 47, Sheet 17, is a detail view in section on a line corresponding to line 47—47 85 of Fig. 46.

Fig. 48, Sheet 17, is a view in section on a line corresponding to line 48—48 of Fig. 46, showing details of a tie wire guide.

Fig. 49, Sheet 17, is a detail view in section on a line corresponding to line 49—49 of Fig. 46, illustrating details of another wire guide.

Fig. 50, Sheet 17, is a detail view in section on a line corresponding to line 50—50 95 of Fig. 47, showing details of a telescopic wire guide.

Fig. 51, Sheet 18, is a detail sectional view of the spring baling chute and wire twisting mechanism in operative position.

Fig. 52, Sheet 5, is an enlarged detail view in section on a line corresponding to line 52—52 of Fig. 1, illustrating details of the transfer mechanism adjusting means.

Fig. 53, Sheet 18, is an enlarged detail 105 view in section on a line corresponding to line 53—53 of Fig. 51.

Fig. 54, Sheet 18, is an enlarged detail view similar to a part of Fig. 51, showing the parts in actuated position.

Fig. 55, Sheet 19, is an enlarged detail view in section on a line corresponding to line 55—55 of Fig. 51.

Fig. 56, Sheet 19, is an enlarged detail view in section on a line corresponding to line 56—56 of Fig. 51.

Fig. 57, Sheet 19, is a fragmentary view of a completed bale of springs.

In the drawing similar reference characters refer to similar parts throughout the several views, and the sectional views are taken looking in the direction of the little arrows at the ends of the section lines.

In my present embodiment, I have illustrated only enough of my spring making machine, hereinbefore referred to, to show the connection of my present invention therewith. By reference to the application mentioned above, it will be noted that the final operation in forming the coil spring 125 130

consists of tying the second loose end of the wire by knotting mechanism which is designated in the present drawing by the numeral 65. The spring 66 is carried to this knoter from the spring knot locating means 67 by a transfer member 68 which is pivoted at 69 to a bracket 70 which is supported by the main frame 71. The ejector formerly used to remove the spring from the machine, 10 has been replaced in the present combination by transfer mechanism forming a part of the baler.

In general, the operation of the baler is as follows:—

15 After a spring has been released by the final knotting mechanism 65, it is grasped by a lifter arm 73 which is pivoted at 74, this lifter arm comprising the first transfer member of the baler. The spring 66 is lifted into range of compressor arms 75 and 76, the arm 75 being raised for a short interval to allow the spring 66 to pass underneath it (see Fig. 4). Plates 77 on the ends of the compressor arms bear against the ends of the spring 66 with sufficient pressure to hold the spring when it is released by the lifter arm 73. The spring is held by the compressor arms until it is grasped by a second transfer member 79 which conveys the 25 spring to the mouth of an assembling chute 80. The approach to the assembling chute is so shaped as to cause the end coils of each spring to enclose the spring preceding it so that the springs are intermeshed and packed 30 closely together (see Fig. 22).

After a predetermined number of springs have been deposited in the assembling chute 80, a flight 81 carried by an endless chain 82 is brought into action to sweep the assembled springs from the assembling chute. The assembled springs slide from the assembling chute into a baling chute 84 which consists of upper and lower sections hinged to each other and to suitable supporting brackets 85. The upper baling chute section 84^a is normally in alignment with the lower end of the assembling chute 80, while the lower section 84^b of the baling chute is in alignment with a baling wire guide 86 through which tie wire 87 is fed to the baling chute. The baling wire is drawn from a suitable source of supply as the spool 88 (see Fig. 5) and is fed to the baling chute by wire feed rollers 90. When the desired amount of wire has entered the baling chute, the wire is brought to rest and is severed by cut-off mechanism 91. The baling chute 84 is provided with tie wire guides, extending the whole length of the chute, the guides being covered by suitable guards to protect them from the springs as the latter slide along the chutes. This will be hereinafter described. After the springs are in position in the baling chute, the lower section 84^b is lifted to a horizontal position and the upper

section 84^a folded down upon the lower section (see dotted outline in Fig. 1) thereby doubling the springs into two rows (see Fig. 51). Wire tying or twisting mechanism 93 is now advanced toward the chute, a plunger 70 head 94 coming into contact with the two rows of springs and compressing them in the chute. Wire guide fingers 95 enter the guides in the chute 84 and pick up the ends of the tie wire 87, directing them to a conical recess 96 formed in the end of a sleeve-like tying member 97. As the tying mechanism 93 reaches the limit of its movement toward the chute 84, a wire clutch 98 carried by a spindle 99 is allowed to snap on to the ends of the wire 87 in the conical recess 96, thereby holding the wire securely and bringing the tying member 97 into frictional engagement with a driven gear 100. The wire clutch and the sleeve-like member are now driven as a unit with the gear 100 and twist the ends of the tie wire together while the tying mechanism is returning to initial position (see Fig. 54), the bale of springs 101 being pulled from the chute 84 by this movement. As the tying mechanism reaches the limit of this return movement, the end of the spindle 99 engages a stationary abutment 102 and pushes the wire clutch 98 back to open position, thereby releasing the ends of the tie wire 87. As the bale 101 is being released from the tying mechanism, an automatic bale ejector 103 is put into action to remove the bale from the machine and leave the way clear for the next advancement of the tying mechanism.

Having described the operation of the baler in general, I shall now give a detail description of the construction and operation of each of the several units.

The lifter arm 73 consists of side members 105 which are pivoted to a stationary pivot rod or post 74 supported by a suitable bracket 107 (see Fig. 8). Gripper jaws 108 are normally held in open position by compression springs 110 (see Fig. 9), which bear against the outer surfaces of the gripper jaws and hold the inner surfaces of the latter in contact with an inwardly tapered section 112 of a gripper jaw actuating member 113, each jaw being yieldingly held parallel with an adjacent face of the tapered section 112. The other end of the actuating member 113 is in the form of an elongated slot 114, enclosing a bushing 115 on the rod 74, which serves as a guide for reciprocation of the member 113. The end 112 is held in central alignment between the ends of opposed guide screws 116 which project through slots 117 in the jaws 108.

The actuating member 113 is reciprocated by a cam member 118 which has a cam slot 119 engaging a roller 120 carried by the member 113 (see Fig. 10). The cam member 118 is fixed to a pinion 122 which is

rotatable on the rod 74. The cam slot 119 is so disposed as to advance the jaws whenever the pinion 122 is turned in one direction, and to cause a reverse movement when the 5 pinion turns in the opposite direction. As the member 113 moves forwardly, the gripper jaws 108 are moved toward the spring 66 in the knotter 65 until the outer ends of the jaws enclose part of the lower coil of the 10 spring. A shoulder 124 on each of the jaws, now comes into contact with a stop 125, preventing further forward movement of the jaws. Continued forward movement of the member 113 causes the wedge-like portion 126 thereof to spread the inner ends of the jaws 108 against tension of the springs 110, thereby causing a lever action, the stops 125 acting as fulcrums and closing the outer ends of the jaws upon the lower coil of the 15 spring 66 (see Fig. 8). The action of the jaws 108 is reversed to release the spring re-tracting movement of the member 113, first allowing the jaws 108 to open and then pulling the jaws to retracted position. One of the 20 jaws 108 is provided with pins 127 to aid in holding the spring 66 in position in the jaws while being transferred (see Fig. 12). The pinion is engaged by a rack 129 which is attached by a pivot connection 130 to a 25 slide 131 reciprocatable in the frame member 132 (see Fig. 8). The slide is moved one way by a cam 133 secured to a counter shaft 134 which is driven from a main shaft 135 of the machine by means of sprockets 136 and 137 and a chain 138 (see Fig. 4). The 30 cam engages a roller 139 which is held by a downwardly projecting pin 140 secured to the slide 131. The roller is held against the cam by tension springs 141 which are secured to the slide 131 and to a stationary 35 part of the machine. When the slide is at its extreme outer position, (see Fig. 3) the lifter arm 73 is in lower position against a stop 142, the gripper jaws 108 being in retracted and open position. One of the side members 105 carries a brake 144 (see Fig. 11) which frictionally engages a collar 145 secured to the rod or post 74 offering sufficient resistance to movement of the lifter 40 arm to cause the pinion 122 and cam member 118 to be actuated before the lifter arm starts moving. Thus when the slide 131 starts moving from its outer position, the rack first actuates the pinion and cam member 45 thereby pushing the gripper jaws 108 toward the spring 66 and closing them upon the lower coil of the spring before the members 105 start moving. After the jaws are closed upon the spring, continued movement 50 of the rack 129 swings the lifter arm 73 to vertical position, carrying the spring 66 into range of the compressor arms 75 and 76. When the spring 66 is in the grasp of the compressor arms, the slide 131 starts moving 55 from its inner position, the result being

first to open the jaws 108, then to pull them away from the spring (see Fig. 18) after which the whole lifter arm swings back to horizontal or receiving position.

The compressor arms 75 and 76 which 70 are pivoted to a supporting arm 146, are actuated by a cam member 147 which is secured to a vertical shaft 148 rotatably mounted in the bracket 149. A bevel gear 150 secured to the other end of the shaft 75 is driven by a bevel pinion 151 carried by the shaft 135. The ratio between the gear and the pinion is such that the cam member 147 makes a half revolution each time a 80 spring is made by the machine. The cam member 147 consists of three working cams or faces, of which the internal cam 153 engages rollers 154 carried by the compressor arms to move the latter in a horizontal plane. Another cam 155 has lifts 156 which engage 85 a roller 157 on the arm 75 to lift this arm while the spring 66 is being passed underneath it by the lifter arm 73 (see Figs. 4, 5 and 14). The cam 153 is made up of duplicate halves, that is, any two points in the 90 working face that are diametrically opposite, are equidistant from the center of rotation. Thus both rollers 154 are at the same distance from the center of the cam at any time and co-operate in holding the spring 66. Each roller is engaged alternately by both 95 halves of the cam. After the spring 66 has been placed in range of the compressor plates 77, and the arm 75 has been dropped back to working position, diametrically opposite portions 153^a of the cam engage the rollers 154 and cause the plates 77 to bear against the 100 ends of the spring with sufficient pressure to hold it when released by the lifter arm 73 (see Fig. 18.) If desired, the dwell 153^a may be 105 continued so that the spring is held without further compression until it is grasped by the second transfer member 79. However, it has been found desirable to subject each 110 spring to greater compression before it is put into assembly in the cushion in order to "set" the spring to insure maintenance of correct length of the spring in use. For this purpose a portion 153^b is incorporated 115 to swing the arms 75 and 76 inwardly far enough to "set" the spring 66, as shown in Fig. 18. A cam portion 153^c now engages the rollers 154 and holds the compressor arms in a position where they will hold the 120 spring 66 until it is within the grasp of the second transfer member 79. A third cam 158 disposed within the internal cam 147 moves the arms to open position when the spring has been engaged by the second transfer member. Upwardly projecting extensions 159 and 160 of the cams 153 and 158 respectively, serve to retain the roller 154 of the arm 75 in position between the cams 125 while this arm is lifted (see Fig. 17).

As a preferred means of pivoting the arms 130

75 and 76 to the supporting arm 146, I have shown ball and socket joints 161 which permit the arms to move in a horizontal plane and at the same time permit lifting of the arm 75. The ball joint members 162 are secured at the arms as by cap screws 163 and are held in place in sockets of the supporting arm 146 by tension springs 164 connecting the compressor arms (see Figs. 15 and 16). Each ball has an elongated slot 165 in which projects one end of a pin 166 which is secured in the arm 146 by a set screw 167. The slots 165 are so disposed as to permit swinging of the arms 75 and 76 in a horizontal plane and lifting of either arm, but to oppose movement of the balls in a vertical plane through the axis of the pin 166. The compressor arms are thus prevented from twisting the plates 77 out of vertical alignment.

The second transfer member includes a lever 170 which is pivoted to the frame base 171, the lower end of the lever being forked to span the baling chute and allow folding of the latter (see Fig. 8). The lever is oscillated by a roller 172 eccentrically located on a crank disc 173 which is secured to the countershaft 134. The roller engages a slot 174 in the side of the lever 170, rotation of the disc causing a crank action to oscillate the lever. The position of the roller 172 on the disc is adjustable to provide means of changing the length of stroke of the lever 170. A preferred means of adjustment is shown in detail in Figs. 28 and 29. The roller is carried by a block 175 which is movable in a dovetail groove 176, a cap screw 177 which forms the pivot of the roller, bearing against the bottom of the slot 176 thereby tightening the block in position.

The upper end of the lever 170 carries a relatively fixed gripping finger 178, and a movable finger 179 which is pivoted at 180. Tension springs 181 tend to pull the movable finger 179 to open position. When the gripping fingers are moved underneath the spring 66 in the compressor plates 77 (see Fig. 1), pressure from an air cylinder 182 against a piston 183 closes the movable finger 179 upon the spring, the finger being connected to the piston by a connecting rod 184 and chain 185 (see Fig. 19). Admission of compressed air to the cylinder 182 is controlled by a valve piston 186 which is opened by means of a chain 187 or other flexible connection when the lever 170 reaches receiving position, an annular groove 188 in the valve piston 186 registering to connect a port 190 with an admission port 191 which leads to a source of air supply 192. The air valve is closed when the lever 170 reaches delivery position by the end of the valve piston 186 coming into contact with an adjustable stop 194. When the valve is closed, a cut away portion 195 of the valve piston registers

with the port 190, providing an outlet for exhaustion of air from the cylinder, thereby permitting the springs 181 to pull the finger 179 to open position (see Fig. 5). A pin 196 projecting into a slot 197 in the valve piston 186 prevents rotation of the latter.

The feed chute consists of an upper wall 198 and a lower wall 199 supported by a bracket 200, the outer edges of the walls being held in spaced relation by tie brackets 201 (see Figs. 1 and 23). Movable sides 202 are held in position by adjusting screws 203 which are threaded in the supporting bracket 200 and the tie brackets 201 (see Fig. 22). The adjusting screws provide means of changing the distance between the sides 202 for springs of different length and to secure the desired tension or compression on the springs. A gradually narrowing entrance to the feed chute is provided by wings 204 which are hinged to the sides 202 and are held in angular position by means of adjusting screws 205 threaded into nuts 206 which are pivoted in brackets 207. The wings bulge slightly at their pivot points 90 thereby compressing the rear side of the spring lying at the mouth of the chute and causing the end coils to lie at such an angle that they are readily enclosed by the spring following. As each spring is added by the transfer member 79, the springs ahead of it are pushed farther down the feed chute and become packed more closely together, the closeness of this packing depending upon the width of space between the adjustable 95 sides.

When the number of springs desired for a bale have been placed in the chute, the ejector flight 81 is moved into the chute 80 and starts shoving the springs out of the chute. The flight is secured to a bracket 209 which is carried by a special link 210 in the ejector chain 82. The upper wall 198 is divided to form a slot 211 through which the flight supporting bracket 209 projects to allow the flight 81 to run through the chute (see Fig. 25). The divided parts of the upper wall are secured to each other by tie brackets 212 which span the chain 82. Certain of the chain links have lateral projections 214 which rest upon the upper surface of the upper wall 198 to support the chain and compel it to follow the contour of the chute (see Fig. 27).

The ejector chain 82 is supported by a drive sprocket 215 and idler sprockets 216 and 217, one of the idler sprockets 216 being so located as to guide the flight 81 into the mouth of the chute. The other idler sprocket 217 is supported by a bracket 218 which is adjustable on the main bracket 200 as a means of tightening the ejector chain (see Fig. 4.) The drive sprocket 215 is intermittently driven from the counter shaft 134 by sprockets 219 and 220, chain 221, driven 120 125 130

shaft 223 and gears 224 and 225 (see Figs. 3, 4 and 6). The driven sprocket 220 is rotatably mounted on the driven shaft 223 and turns idly except when connected to the shaft 5 by a clutch.

A suitable clutch is illustrated in detail in Figs. 30 to 34 inclusive. A clutch pin 226 is normally held in a recess in a collar 227, by a release member 228 carried by a clutch 10 lever 229. The releasing member rests in an annular groove 230 in the collar 227 and engages a notch 231 in the pin 226. When the releasing member is lifted out of the notch 231, the clutch pin is projected by a compression spring 232 into range of a driving pin 233 which is carried by the driven sprocket 220. The driving pin 233 engages the pin 226 and rotates the driven shaft 223 until the release member 228 is again 20 let down into range of the clutch pin. One side of the notch 231 then engages a beveled surface 234 on the release member and wedges the clutch pin back into the recess in the collar 227 bringing the driven shaft 223 to rest. The clutch lever is pivoted to a shaft 235 which is also secured to a cam lever 236. The cam lever carries a roller 237 which is held in contact with a cam 238 by a tension spring 239. The cam 238 is rotatably mounted on a sleeve bearing 240 on the frame member 232. The cam has a cut away portion 241 into which the roller 237 drops to allow the spring 239 to actuate the clutch lever and lift the release member 228 out of 30 the clutch pin 226, thereby permitting engagement of the clutch, the clutch being disengaged again when the roller is lifted out of this cut away portion in the cam.

The cam 238 may be actuated by any 40 driving means that works in timed relation to the placing of springs in the assembly chute 80. A convenient driving means is afforded by the mechanism which oscillates the transfer member 68 of my spring making machine.

A sprocket 243 which is secured to the pivot rod of the member 68, is engaged by a chain 244 which is connected with a cam lever 245 by an adjustable connecting rod 246 and with one end of a rock lever 247 by another connecting rod 248 (see Figs. 1, 2 and 5). The other end of the lever 247 is connected by a rod 249 to a piston 250 which is urged upward by pressure from a compressed air cylinder 251. A cam 252 secured to a counter shaft 253, engages a roller 254 on the cam lever 245 to move the chain 244 in one direction, the roller being 50 yieldingly held in contact with the cam and the chain pulled in the other direction by the air pressure against the piston 250. This oscillatory movement of the chain 244 causes the sprocket 243 to oscillate the transfer member 68 between the knot locating means 67 and the second knotter 65.

The cam 238 is operatively connected with the driving means just described by a ratchet lever 255 which is pivoted on a hub of the cam and carries a pawl 256 engaging a ratchet wheel 257 which is fixed to the cam. The ratchet lever is normally held down against a stop 258 by a spring 259 (see Fig. 35). The outer end of the lever is in range of a tappet 260 which is adjustably secured to the connecting rod 248. When the rod 248 is pulled upward by the chain 244, the lever 255 is lifted, thereby turning the ratchet wheel a certain distance (see Fig. 1). When the rod 248 moves downward, the lever 256 drops back against the stop 258 bringing the pawl 256 into engagement with another tooth of the ratchet wheel 257. The ratchet wheel is prevented from rotating backward by a pawl 261 which is pivoted to a stationary bracket 262 and held against the wheel by a spring 263.

Since the tappet 260 is raised each time a spring is made by the machine, the number of teeth in the ratchet wheel 247 must correspond to the number of springs put into a bale, the cam 238 turning one revolution for each bale of springs. When the cam roller 237 is engaged by the working portion 241 of the cam 238, thereby causing engagement of the clutch, the sprocket 220 starts driving the ejector chain 82 which continues moving until the clutch is disengaged by the roller being lifted out of the portion 241 of the cam. The length of the cam portion 241 bears the correct relation between the rate of rotation of the cam and the speed ratio of the ejector chain driving means, to cause the chain to make exactly one revolution so that the flight 81 always stops at the same place.

After the springs are cleared from the assembling chute 80, they slide into the balancing chute 84, occupying the position shown diagrammatically by dotted lines in Fig. 5. The chute has already been supplied with tie wire for binding the bale.

The wire feed rollers 90 consist of an upper roller 90^a and lower roller 90^b. The roller 90^a is secured to a shaft 265 which is journaled in a housing 266. The shaft 265 is operatively connected with another shaft 267 by sprockets 268 and chain 270. A driven sprocket 271 on the shaft 267 is connected by a chain 272 to a driving sprocket 273 on the cam shaft 253. The lower roller 90^b is keyed to a shaft 275 which is journaled in bearing blocks 276 reciprocable in guides in the housing 266. The lower shaft 275 is driven constantly by the upper shaft 265 through gears 277. The roller 90^b is normally held out of frictional engagement with the roller 90^a by compression springs 278, the wire remaining at rest at this time, although the feed rolls are not separated far enough to place the gears 277

out of mesh. The lower roller is brought into engagement with the upper roller as desired by a cam lever 280 which carries adjusting screws 281 supporting the bearing blocks 276. The lever 280 is actuated by a cam 282 which is secured to a cam shaft 283. The cam shaft 283 is operatively connected by sprockets 284 and chain 285 to a shaft 286 which carries a worm wheel 287. The 10 worm wheel is driven by a worm 288 operatively keyed to a driven shaft 289 which is turned by a bevel gear 290 in mesh with a companion gear 291 on the shaft 267. The wire feed cam 282 turns at the same 15 speed as the worm wheel 287, the rise of the cam being designed to hold the feed rollers in engagement with the wire 87 the proper length of time to feed the desired amount of wire to the baling chute 84, the adjusting screws 281 co-operating to accurately determine this result.

The feed rollers 90 draw the wire 87 from a suitable source of supply as the spool 88 shown in Fig. 5, and force the wire through 25 stationary guides 294 and 295 and a movable guide 296, forming part of the wire cut-off mechanism 91. The cut-off 296 is pivoted to a bracket 297 and normally held in alignment with the final stationary guide 30 which constitutes a shear block by a spring 298. The cut-off 296 is swung on its pivot by a roller 299 carried by a slide member 300. The slide member is reciprocated by a cam 301 which is secured to the wire 35 feed control cam shaft 283, the cam engaging a cam roller 302 carried by the yoke end of a connecting rod 303 which is attached to the slide member 300 by a hinged joint 304. A spring 304' returns the slide to its 40 initial position. When the slide member is moved toward the cam shaft, the roller engages a bevel surface 305 on the cut-off 296, forcing the latter out of alignment with the stationary guide 30. The end of a wire 45 guide bushing 306 carried by the cut-off 296 bears closely against the end of the bushing 307 in the guide 30. When these parts are forced out of alignment with each other, a shearing action occurs which severs 50 the wire 87 (see Fig. 45). The stationary bushing 307 may be adjusted relative to the movable bushing 306 by means of a thrust screw 308 which is threaded in the member 30, the bushing 307 being held in adjusted 55 position by set screw 309 (see Fig. 41).

The worm wheel 287 which times both the feeding and the cut-off operation, rotates at the same rate of the cam 283 so that the tie wire is supplied to the baling chute 84 in 60 timed relation to the movement of springs into the chute.

The baling chute wire guides which are 65 similar in both sections of the baling chute 84 are shown in detail in Figs. 46 to 50 and Fig. 55. A guide member extending the

greater length of each chute section, consists of separate opposed sections 310, normally held in contact with each other by springs 311. These sections 310 are supported by guide links 312 pivoted on pins 313 in the guide member and on pins 314 in a base plate 315 of the chute co-operating with stop pins 316 to hold the adjacent faces of the guide members 310 in alignment with the center line of the chute (see Fig. 46). The adjacent faces of the guide members are grooved to form a suitable passage for the wire 87 when the faces are in contact (see Fig. 48). The guide members are housed by guard strips 318 to keep the springs 66 from becoming lodged in the guide mechanism as the springs slide along the chute. Adjacent the inner end of these guide members I provide another wire guide 320 formed by opposed plungers 321, each plunger being arranged in a recess in a bracket 322. The springs 323 tend to push the plungers 321 toward each other, the adjacent ends of the plungers being grooved to form a passage for the wire 87. This 90 passage is aligned with the other guides by stop pins 324 which project into slots 325 in the plungers 321 to limit the outward movement and prevent rotation of the latter (see Fig. 55). When the baling chute 95 is in open position, the adjacent end portions of the sections 310 and 310' are telescoped (see Figs. 1, 5 and 6). The wire guide at this point is formed by a guide section 326 secured to the lower chute section 310 and another guide section 327 carried by the upper chute section 310'. The adjacent faces of these guide sections which are in contact when the chute is in open 100 position are grooved to form the passage 105 for the wire (see Figs. 50-55). The tie wire 87 enters the lower end of the chute section 310, passes through the several guides and stops with the end of the wire near the end of the upper chute section 310'. A wire 110 clutch located in the upper chute section permits wire to advance through the guides but prevents backward movement of the wire. This wire clutch consists of grippers 330 pivoted at 331, springs 332 holding the 115 ends of the grippers against the wire at such an angle as to allow forward movement, but to prevent backward movement of the wire. Stop pins 333 limit the swinging of the grippers when the wire is removed. When the chutes are being folded, the wire grippers 330 hold the wire 87 in place in the upper chute 310, but pull wire through the guides in the lower chute 310' to 120 compensate for the extra amount of wire required to reach around the baling chute when in folded position (see Fig. 51). The point at which the wire 87 is severed by the cut-off mechanism 91 is located the correct distance from the end of the chute 310' 130

to cause the end of the wire to reach a desired point in the chute when the latter is folded. The stationary wire guide 86 is open at the top and the frame plate above is slotted to permit the wire to be lifted out of the guide 86 as the lower chute is lifted to horizontal position (see Figs. 5 and 44).

When in open position, the lower chute rests upon a stop 335 which is adjustable for accurately aligning the guide 310 with the guide 86. The chute 84^b is lifted by a rock lever 336 pivoted at 337 to the frame base 171. One end of the lever terminates in a curved head 338 lying underneath the chute, the other end carrying a cam roller 339 in contact with a cam 340 which is secured to a shaft 341. This shaft is operatively connected by gears 342 to a driven shaft 343 upon which a sprocket 344 is rotatably mounted. This sprocket 344 is driven by the chain 221 which also drives the sprocket 220 of the assembling chute ejecting mechanism. The sprocket 344 normally rotates idly on the driven shaft 343 but may be made to drive the shaft by engagement of a clutch 345 which corresponds to the clutch used in the driving mechanism of the ejector chain 82. The clutch 345 is controlled by a cam lever 346 which has a roller 347 resting upon the cam 238. After the cam 238 has caused the ejector flight 81 to clear the springs from the assembling chute 80, the working portion 241 of the cam engages the cam roller 347 allowing the cam lever spring 348 to throw the clutch 345 into engagement thereby causing the shaft 341 to be driven. The speed ratio of the driving mechanism of the shaft 341 bears the correct relation to the cam 238 to cause the shaft to be rotated exactly one revolution each time a bale is formed.

The upper chute section 84^a is held open by a cam 350 which engages a roller 351 carried by a rock arm 352 which is connected to the chute by a connecting rod 353. When in open position, the chute rests on a roller 354 which is rotatably mounted on an extension of the clutch shaft 343. When the cam shaft 341 starts rotating, the rock arm 352 is released by the cam 350 and a spring 355 attached to the rock arm and anchored to a frame member, starts swinging the chute 84^a to folded position, the weight of the chute aiding this action after it is partly closed. The baling chute is shown folded in Fig. 51 and, by dotted lines, in Fig. 1.

As the baling chute is being folded, the wire twisting mechanism 93 advances toward the chute 84. This mechanism is mounted on a carriage 356 which is reciprocatable on a track 357 formed on the frame base 171, the carriage being supported in dovetail ways 358 (see Fig. 44).

A preferred means of moving the carriage is illustrated in Figs. 1, 6, 7 and 40. A rack

360 secured to the base of the carriage 356 is engaged by a gear 361 which also meshes with a stationary rack 362 secured to the frame base 171. An intermediate rack 363 has one end pivoted to the gear 361, the teeth on the underside of the rack meshing with a smaller gear 364 which also engages the stationary rack 362. A pinion 365 carried by the intermediate rack 363, engages the rack 360 to hold the parts in assembled relation. The gear 364 is rotatably secured to one end of a connecting rod 366, the other end of the rod being pivoted on a crank pin 367 carried by a disc 368 on the end of the cam shaft 341. When the disc 368 revolves, the small gear 364 is moved along the stationary rack 362, the teeth of the gear moving the intermediate rack 363 double the distance that the center of the gear is moved by the connecting rod 366. Likewise the large gear 361 moves the carriage 356 double the distance traveled by the intermediate rack 363, the result being that the carriage moves four times the distance traveled by the lower end of the connecting rod. The means of adjusting the position of the crank pin 367 on the disc 368 to change the distance traveled by the carriage is shown in detail in Fig. 52. This adjustment is similar to that illustrated and described herein in connection with the means of oscillating the second transfer member 79.

The wire twisting mechanism is illustrated in detail in Figs. 51, 53 and 54. The spindle 99 to which the clutch member 98 is secured is reciprocatable in the tying member 97 which is also reciprocatable in the carriage 356. The wire clutch member 98 is normally held out of the conical recess 96 by a lock lever 370 which is pivoted to the frame 356 and has a tooth 371 engaging a collar 372 on the shaft 99. A spring 373 between the collar 372 and a thrust bearing 374, holds the collar in contact with the lever tooth 371, the face of the collar being concave to aid in holding the parts in locked position. The collar is adjustably held in position on the shaft 99 by a nut 375. The driven gear 100 which normally rotates idly on the sleeve member 97, is driven constantly by a gear 376 which is secured to the worm shaft 289. This shaft extends a considerable distance through the worm 288 and bevel gear 290. Keys 377 in the worm and gear rest loosely in a key way 378 in the shaft 289 so that the shaft may slide with the carriage 356 and at the same time maintain driving relation with the gear and the worm.

The wire twisting mechanism advances toward the chute with the clutch member 98 in open position. The plunger head 94 pushes the springs 66 ahead of it and compresses them tightly in the folded chute. The wire pick up or guide fingers 95 engage the ends of the wire guide sections 310, forcing

them apart and moving along the opening between the guide members (see Fig. 55) picking up the wire 87 and guiding the ends of the wire to the conical recess 96 of the twister. With the movable guides 310 open, the wire is free to be pulled closely around the bale, the springs of the plunger guides 320 yielding to allow separation of the plungers, and the telescopic guide sections being now separated and no longer holding the wire.

As the twisting mechanism reaches the limit of its movement into the chute, the lock lever 370 is tripped permitting the clutch spring 373 to reciprocate the shaft 99 and pull the clutch member 98 against the ends of the wire 87 in the conical recess 96. A means of tripping the lock lever consists of a push member 380, pivoted to parallel links 381 which are mounted on the carriage 356. Tappets 382 on the member 380, come into contact with the end of the chute section 84^a as the twisting mechanism enters the baling chute causing the member 380 to push the lock lever 370 to open position. The tappets may be clamped in any desired position (see Fig. 53) to accurately time the tripping of the wire clutch member 98. When the clutch member 98 is drawn into the tying member 97, the latter is brought into frictional engagement with the driven gear 100 which starts rotating the tying member and the clutch member as a unit. Pins 384 projecting from the clutch member 98, gather in the end portions of the tie wire and cause them to be drawn down around the clutch member and twisted together (see Fig. 54). The twisting operation continues while the carriage 356 is moving back to initial position, the bale of springs being pulled from the chute.

When the carriage reaches the limit of this backward movement, the end of the spindle 99 encounters the abutment 102 on the housing 266, pushing the wire clutch member 98 back to open position and thereby releasing the ends of the wire. A tension spring 386 attached to the upper end of the lock lever 170 pulls the latter back to engagement with the collar 372. With the wire released from the twisting mechanism, the bale of springs which is shown in Fig. 57, is now free to be removed from the machine.

A preferred means of ejecting the bale of springs from the machine is illustrated in Figs. 1, 5 and 7. It consists of the lever 103 pivoted at 388 to the frame base 171, one end terminating in a jaw 389 for engaging the bale. The end 389 of the lever is normally held out of range of the twisting mechanism by a latch 390 which is pivoted at 387 and engages the other end 391 of the lever 103, the latch being held toward the lever by a spring 392 carried by a spring keeper 393 on which adjustable stop nuts 394 are

threaded. As the carriage 356 reaches the limit of its movement away from the baling chute, an adjustable tappet 395 on the carriage comes into contact with the latch 390 and forces the latter out of engagement with the end 391 of the lever 103, allowing a tension spring 396 to swing the lever and strike the end 389 against the bale of springs with sufficient force to knock the bale off the way 357. The ejector lever 103 is reset by a pin 397 or other abutment on the carriage 356 which forces the lever back to set position as the carriage advances toward the baling chute (see dotted outline in Fig. 7).

I have illustrated and described an embodiment of my invention which I regard as very satisfactory. I have not attempted to illustrate or describe various modifications in structural details which I contemplate and which might be desirable under certain conditions as I believe the disclosure made will enable those skilled in the art to which my invention relates to embody or adapt the same as may be desired.

Having thus described my invention what I claim as new and desire to secure by Letters Patent is:

1. In a structure of the class described, the combination with an assembling chute, of means for feeding springs thereto whereby they are assembled in nested relation therein, means for ejecting the assembled springs from said assembling chute, a baling chute comprising a pair of pivoted sections, the forward section being supported when in open position in alignment with said assembling chute and being adapted to swing rearwardly upon the rear section, the rear section being movable to and from wire receiving position, a wire feed means, a wire cut-off means, wire guides for said baling chute sections each comprising a pair of guide members having guide grooves in their opposed faces, supporting links for said guide members whereby they are supported for parallel movement, springs normally holding said guide members in closed position, a wire clutch member for the forward baling section, means for closing said forward chute section upon the coacting section, a reciprocating carriage, a tying member rotatably mounted in said carriage and having a conical recess in its forward end, a driving means for said tying member permitting the reciprocation of said carriage, diverging wire pick-up fingers adapted to open said wire guides of said baling chute sections and guide the wire into said conical recess of said tie member, a wire clutch member reciprocatingly supported within said tying member and adapted to clamp the ends of the wire thereto, said clutch member being provided with laterally disposed wire engaging pins, means for releasing and locking said clutch member in inoperative position

on the return stroke of the carriage, means 5 for releasing said clutch member locking means on the forward movement of said carriage, a plunger on said carriage adapted to compress the springs within the closed chute sections, and means for reciprocating said carriage, whereby the same is advanced to compress the springs within the chute and engage the wires with said tying device, the 10 bale being withdrawn from the chute on the retracting movement of the carriage.

2. In a structure of the class described, the combination with an assembling chute, of means for feeding springs thereto whereby they are assembled in nested relation therein, means for ejecting the assembled 15 springs from said assembling chute, a baling chute comprising a pair of pivoted sections, the forward section being supported when in open position in alignment with said assembling chute and being adapted to swing rearwardly upon the rear section, the rear section being movable to and from wire receiving position, a wire feed means, a wire 20 cut-off means, wire guides for said baling chute sections, a wire clutch member for the forward baling section, means for closing said forward chute sections upon the coacting section, a reciprocating carriage, a tying member 25 rotatably mounted in said carriage and having a conical recess in its forward end, a driving means for said tying member permitting the reciprocation of said carriage, diverging wire pick-up fingers adapted to open said wire guides of said baling chute sections and guide the wire into said conical 30 recess of said tie member, a wire clutch member reciprocatingly supported within said tying member and adapted to clamp the ends of the wire thereto, said clutch member being provided with laterally disposed wire 35 engaging pins, and means for reciprocating said carriage.

3. In a structure of the class described, the combination with an assembling chute, of means for feeding springs thereto whereby they are assembled in nested relation therein, means for ejecting the assembled 40 springs from said assembling chute, a baling chute comprising a pair of pivoted sections, the forward section being supported when in open position in alignment with said assembling chute and being adapted to swing rearwardly upon the rear section, the rear section being movable to and from wire receiving position, a wire feed means, a wire 45 cut-off means, wire guides for said baling chute sections, a wire clutch member for the forward baling section, means for closing said forward chute sections upon the coacting section, a reciprocating carriage, a tying member 50 rotatably mounted in said carriage and having a conical recess in its forward end, a driving means for said tying member permitting the reciprocation of said carriage, diverging wire pick-up fingers adapted to guide the wire into said conical recess of said tie member, a wire clutch member reciprocatingly supported within said tying member and adapted to clamp the ends of the wire 55 thereto, said clutch member being provided with laterally disposed wire engaging pins, and means for reciprocating said carriage.

4. In a structure of the class described, the combination with an assembling chute, of means for feeding springs thereto whereby they are assembled in nested relation therein, means for ejecting the assembled 60 springs from said assembling chute, a baling chute comprising a pair of pivoted sections, the forward section being supported when in open position in alignment with said assembling chute and being adapted to swing rearwardly upon the rear section, the rear section being movable to and from wire receiving position, a wire feed means, a wire 65 cut-off means, wire guides for said baling chute sections, a wire clutch member for the forward baling section, means for closing said forward chute sections upon the coacting section, a reciprocating carriage, a tying member rotatably mounted in said carriage and having a conical recess in its forward end, a driving means for said tying member permitting the reciprocation of said carriage, diverging wire pick-up fingers adapted to guide the wire into said conical recess of said tie member, a wire clutch member reciprocatingly supported within said tying member and adapted to clamp the ends of the wire thereto, said clutch member being provided with laterally disposed wire engaging pins, and means for reciprocating said carriage.

5. In a structure of the class described, the combination with an assembling chute, of means for feeding springs thereto whereby they are assembled in nested relation therein, means for ejecting the assembled 70 springs from said assembling chute, a baling chute comprising a pair of pivoted sections, the forward section being supported when in open position in alignment with said assembling chute and being adapted to swing rearwardly upon the rear section, the rear section being movable to and from wire receiving position, a wire feed means, a wire 75 cut-off means, wire guides for said baling chute sections each comprising a pair of guide members having guide grooves in their opposed faces, supporting links for said 80 guide members whereby they are supported for parallel movement, springs normally holding said guide members in closed position, a wire clutch member for the forward baling section, means for closing said forward chute section upon the coacting section, a reciprocating carriage, a tying member 85 rotatably mounted in said carriage and having a conical recess in its forward end, a driving means for said tying member permitting the reciprocation of said carriage, diverging wire pick-up fingers adapted to open said wire guides of said baling chute sections and guide the wire into said conical recess of said tie member, a wire clutch member reciprocatingly supported within said tying member and adapted to clamp the ends of the wire thereto, said clutch member being provided with laterally disposed wire 90 engaging pins, and means for reciprocating said carriage.

6. In a structure of the class described, the combination with an assembling chute, of means for feeding springs thereto whereby they are assembled in nested relation therein, means for ejecting the assembled 95 springs from said assembling chute, a baling chute comprising a pair of pivoted sections, the forward section being supported when in open position in alignment with said assembling chute and being adapted to swing rearwardly upon the rear section, the rear section being movable to and from wire receiving position, a wire feed means, a wire 100 cut-off means, wire guides for said baling chute sections, a wire clutch member for the forward baling section, means for closing said forward chute sections upon the coacting section, a reciprocating carriage, a tying member 105 rotatably mounted in said carriage and having a conical recess in its forward end, a driving means for said tying member permitting the reciprocation of said carriage, diverging wire pick-up fingers adapted to guide the wire into said conical recess of said tie member, a wire clutch member reciprocatingly supported within said tying member and adapted to clamp the ends of the wire 110 thereto, said clutch member being provided with laterally disposed wire engaging pins, and means for reciprocating said carriage.

7. In a structure of the class described, the combination with an assembling chute, of means for feeding springs thereto whereby they are assembled in nested relation therein, means for ejecting the assembled 115 springs from said assembling chute, a baling chute comprising a pair of pivoted sections, the forward section being supported when in open position in alignment with said assembling chute and being adapted to swing rearwardly upon the rear section, the rear section being movable to and from wire receiving position, a wire feed means, a wire 120 cut-off means, wire guides for said baling chute sections each comprising a pair of guide members having guide grooves in their opposed faces, supporting links for 125

guide grooves in their opposed faces, supporting links for said guide members whereby they are supported for parallel movement, springs normally holding said guide members in closed position, a wire clutch member for the forward baling section, means for closing said forward chute section upon the coacting section, a reciprocating carriage, a tying member 130 rotatably mounted in said carriage and having a conical recess in its forward end, a driving means for said tying member permitting the reciprocation of said carriage, diverging wire pick-up fingers adapted to open said wire guides of said baling chute sections and guide the wire into said conical recess of said tie member, a wire clutch member reciprocatingly supported within said tying member and adapted to clamp the ends of the wire thereto, said clutch member being provided with laterally disposed wire engaging pins, and means for reciprocating said carriage.

8. In a structure of the class described, the combination with an assembling chute, of means for feeding springs thereto whereby they are assembled in nested relation therein, means for ejecting the assembled springs from said assembling chute, a baling chute comprising a pair of pivoted sections, the forward section being supported when in open position in alignment with said assembling chute and being adapted to swing rearwardly upon the rear section, the rear section being movable to and from wire receiving position, a wire feed means, a wire cut-off means, wire guides for said baling chute sections each comprising a pair of guide members having guide grooves in their opposed faces, supporting links for 135

5 said guide members whereby they are supported for parallel movement, springs normally holding said guide members in closed position, a wire clutch member for the forward baling section, means for closing said forward chute section upon the coacting section, a reciprocating carriage, a tying member 10 rotatably mounted in said carriage and having a recess in its forward end, a driving means for said tying member permitting the reciprocation of said carriage, diverging wire pick-up fingers adapted to open said wire guides of said baling chute sections and guide the wire into said conical recess of said tie member, and a wire clutch member reciprocatingly supported within said tying member and adapted to clamp the ends of the wire thereto.

15 10 means for said tying member permitting the reciprocation of said carriage, diverging wire pick-up fingers adapted to open said wire guides of said baling chute sections and guide the wire into said conical recess of said tie member, a wire clutch member reciprocatingly supported within said tying member and adapted to clamp the ends of the wire thereto, said clutch member being provided with laterally disposed wire engaging pins, means for releasing and locking said clutch member in inoperative position on the return stroke of the carriage, and means for releasing said clutch member locking means on the forward movement of said carriage.

20 15 25 30 35 40 45 50 55 60 65 66 67 68 69 70 75 80 85 90 95 100 105 110 115 120 125 130

6. In a structure of the class described, the combination of a baling chute comprising a pair of pivoted sections, the forward section being adapted to swing rearwardly upon the rear section, a wire feed means, a wire cut-off means, wire guides for said baling chute sections, means for closing said forward chute section upon the coacting section, a reciprocating carriage, a tying member rotatably mounted in said carriage and having a recess in its forward end, a driving means for said tying member permitting the reciprocation of said carriage, wire pick-up fingers adapted to guide the wire into said conical recess of said tie member, a wire clutch member reciprocatingly supported within said tying member and adapted to clamp the ends of the wire thereto, said clutch member being provided with laterally disposed wire engaging pins, means for releasing and locking said clutch member in inoperative position on the return stroke of the carriage, and means for releasing said clutch member locking means on the forward movement of said carriage.

7. In a structure of the class described, the combination of a baling chute comprising a pair of pivoted sections, the forward section being adapted to swing rearwardly upon the rear section, a wire feed means, a wire cut-off means, wire guides for said baling chute sections each comprising a pair of guide members having guide grooves in their opposed faces, supporting links for said guide members whereby they are supported for parallel movement, springs normally holding said guide members in closed position, a wire clutch member for the forward baling section, means for closing said forward chute section upon the coacting section,

a reciprocating carriage, a tying member rotatably mounted in said carriage and having a recess in its forward end, a driving means for said tying member permitting the reciprocation of said carriage, diverging wire pick-up fingers adapted to open said wire guides of said baling chute sections and guide the wire into said conical recess of said tie member, and a wire clutch member reciprocatingly supported within said tying member and adapted to clamp the ends of the wire thereto.

8. In a structure of the class described, the combination of a baling chute comprising a pair of pivoted sections, the forward section being adapted to swing rearwardly upon the rear section, a wire feed means, a wire cut-off means, wire guides for said baling chute sections, means for closing said forward chute section upon the coacting section, a reciprocating carriage, a tying member rotatably mounted in said carriage and having a recess in its forward end, a driving means for said tying member permitting the reciprocation of said carriage, wire pick-up fingers adapted to guide the wire into said conical recess of said tie member, and a wire clutch member reciprocatingly supported within said tying member and adapted to clamp the ends of the wire thereto.

9. In a structure of the class described, the combination with means for assembling springs in nested relation, of a baling chute to which the springs are delivered from said assembling means comprising a pair of pivoted sections having curved end portions adapted to telescope when the sections are in open position, means for collapsing the forward section upon the rear section, the rear section being pivotally supported, main guide wires mounted upon said sections and comprising a pair of wire guide members mounted for parallel opening and closing movement, said guides being provided with grooves in their coacting faces, coacting wire guides on the curved portions of said chute sections, said guide members on their curved sections being adapted to open and close with a telescoping movement, plunger-like guide members interposed between said guide members on said curved section and said main guides, said plunger-like guide members being arranged in coacting pairs and yieldingly supported, a wire clutch means on said forward section, a reciprocating carriage, a wire tying means carried thereby, said carriage being provided with means for engaging the wire and release it from said guides on the forward stroke of the carriage, said carriage being adapted to compress the springs within the chute on the forward movement thereof and withdraw the bale on the return movement thereof.

10. In a structure of the class described, the combination with means for assembling

- 7 springs in nested relation, of a baling chute to which the springs are delivered from said assembling means comprising a pair of pivoted sections having curved end portions 5 adapted to telescope when the sections are in open position, means for collapsing the forward section upon the rear section, the rear section being pivotally supported, main wire guides mounted upon said sections and 10 comprising a pair of wire guide members mounted for parallel opening and closing movement, said guides being provided with grooves in their coacting faces, coacting wire guides on the curved portions of said chute 15 sections, said guide members on said curved section being adapted to open and close with a telescoping movement, a wire clutch means on said forward section, a reciprocating carriage, a wire tying means carried thereby, 20 said carriage being provided with means for engaging the wire and release it from said guides on the forward stroke of the carriage, said carriage being adapted to compress the springs within the chute on the forward 25 movement thereof and withdraw the bale on the return movement thereof.
11. In a structure of the class described, the combination of a baling chute comprising a pair of pivoted sections having curved 30 end portions adapted to telescope when the sections are in open position, means for collapsing the forward section upon the rear section, main wire guides mounted upon said sections and comprising a pair of wire guide 35 members mounted for parallel opening and closing movement, said guides being provided with grooves in their coacting faces, coacting wire guides on the curved portions of said chute sections, said guide members on 40 said curved section being adapted to open and close with a telescoping movement, plunger-like guide members interposed between said guide members on said curved section and said main guides, said plunger-like 45 guide members being arranged in coacting pairs and yieldingly supported, and a wire clutch means on said forward section.
12. In a structure of the class described, the combination of a baling chute comprising a pair of pivoted sections having curved 50 end portions adapted to telescope when the sections are in open position, means for collapsing the forward section upon the rear section, main wire guides mounted upon said sections and comprising a pair of wire guide 55 members mounted for parallel opening and closing movement, said guides being provided with grooves in their coacting faces, and coacting wire guides on the curved portions of said chute sections, said guide members on 60 said curved section being adapted to open and close with a telescoping movement.
13. In a structure of the class described, the combination of a baling chute comprising 65 a pair of pivoted sections having curved end portions adapted to telescope when the sections are in open position, means for collapsing the forward section upon the rear section, and coacting wire guides on the curved portions of said chute sections, said 70 guide members on said curved section being adapted to open and close with a telescoping movement.
14. In a structure of the class described, the combination with an assembling chute, 75 of means for feeding the springs thereto whereby they are assembled in nested relation therein, means for ejecting the assembled springs from said assembling chute, a baling chute comprising a pair of pivoted 80 sections, the forward section being supported when in open position in alignment with said assembling chute and being adapted to swing rearwardly upon the rear section, the rear section being movable to and from wire 85 receiving position, a wire feed means, a wire cut-off means, wire guides on said baling chute sections, means for closing said forward chute section upon the coacting section, a reciprocating carriage, a tying means 90 carried by said carriage, a plunger on said carriage adapted to compress the springs within the closed chute sections, and means for reciprocating said carriage whereby the 95 same is advanced to compress the springs within the chute and engage the wires with said tying device, the bale being withdrawn from the chute on the retracting movement of the carriage.
15. In a structure of the class described, the combination with an assembling chute, 100 of means for feeding springs thereto whereby they are assembled in nested relation therein, means for ejecting the assembled springs from said assembling chute, a baling chute comprising a pair of pivoted sections, the forward section being supported when 105 in open position in alignment with said assembling chute and being adapted to swing rearwardly upon the rear section, a wire feed means, means for closing said forward chute section upon the coacting section, a reciprocating carriage, a tying means carried by said carriage, a plunger on said carriage adapted to compress the springs within 110 the closed chute sections, and means for reciprocating said carriage whereby the same is advanced to compress the springs within the chute and engage the wires with said tying device, the bale being withdrawn from the chute on the retracting movement of the carriage.
16. In a structure of the class described, the combination with an assembling chute, 115 of means for feeding springs thereto whereby they are assembled in nested relation therein, means for ejecting the assembled springs from said assembling chute, a baling 120 chute comprising a pair of pivoted sections, the forward section being supported when in open position in alignment with said assembling chute and being adapted to swing rearwardly upon the rear section, a wire feed means, means for closing said forward chute section upon the coacting section, a reciprocating carriage, a tying means carried by said carriage, a plunger on said carriage adapted to compress the springs within the closed chute sections, and means for reciprocating said carriage whereby the same is advanced to compress the springs within the chute and engage the wires with said tying device, the bale being withdrawn from the chute on the retracting movement of the carriage.
17. In a structure of the class described, the combination with an assembling chute, 125 of means for feeding springs thereto whereby they are assembled in nested relation therein, means for ejecting the assembled springs from said assembling chute, a baling

- chute comprising a pair of pivoted sections, the forward section being supported when in open position in alignment with said assembling chute and being adapted to swing rearwardly upon the rear section, a wire feed means, means for closing said forward chute section upon the coacting section, a reciprocating carriage, and a tying means carried by said carriage. 5
- 10 17. In a structure of the class described, the combination of a baling chute comprising a pair of pivoted sections, the forward section being adapted to swing rearwardly upon the rear section, the rear section being movable to and from wire receiving position, a wire feed means, a wire cut-off means, wire guides on said baling chute sections, means for closing said forward chute section upon the coacting section, a reciprocating carriage, a tying means carried by said carriage, a plunger on said carriage adapted to compress the springs within the closed chute sections, and means for reciprocating said carriage whereby the same is advanced to compress the springs within the chute and engage the wires with said tying device, the bale being withdrawn from the chute on the retracting movement of the carriage. 20
- 25 18. In a structure of the class described, the combination of a baling chute comprising a pair of pivoted sections, the forward section being adapted to swing rearwardly upon the rear section, a wire feed means, means for closing said forward chute section upon the coacting section, a reciprocating carriage, a plunger on said carriage adapted to compress the springs within the closed chute sections, and means for reciprocating said carriage whereby the same is advanced to compress the springs within the chute and engage the wires with said tying device, the bale being withdrawn from the chute on the retracting movement of the carriage. 30
- 35 19. In a structure of the class described, the combination with an assembling chute, of means for feeding springs thereto whereby they are assembled in nested relation therein, means for ejecting the assembled springs from said assembling chute, a baling chute comprising a pair of pivoted sections, the forward section being supported when in open position in alignment with said assembling chute and being adapted to swing rearwardly upon the rear section, the rear section being movable to and from wire receiving position, a wire feed means, a wire cut-off means, and a wire tying means. 40
- 45 20. In a structure of the class described, the combination with an assembling chute, of means for feeding springs thereto whereby they are assembled in nested relation therein, means for ejecting the assembled springs from said assembling chute, a baling chute comprising a pair of pivoted sections, the forward section being supported when in open position in alignment with said assembling chute and being adapted to swing rearwardly upon the rear section, and a wire tying means. 50
- 55 21. In a structure of the class described, the combination with an assembling chute, means for feeding springs thereto whereby they are assembled in nested relation, means for ejecting the assembled springs from said assembling chute, a baling chamber to which the assembled springs are delivered from said chute comprising a pair of sections adapted to be collapsed one upon the other whereby the assembled springs are folded together with a wire about the same, a reciprocating carriage, a wire tying means carried thereby, said carriage being adapted to compress the springs within the baling chamber on the forward movement of the carriage and engage the tying wires, and means for releasing the wires on the return movement of the carriage whereby the bale is withdrawn from the baling chamber. 60
- 65 22. In a structure of the class described, the combination with an assembling chute, means for feeding springs thereto whereby they are assembled in nested relation, means for ejecting the assembled springs from said assembling chute, a baling chamber to which the assembled springs are delivered from said chute comprising a pair of sections adapted to be collapsed one upon the other whereby the assembled springs are folded together with a wire about the same. 70
- 75 23. In a structure of the class described, the combination of a baling chamber comprising a pair of sections adapted to be opened to receive springs assembled in nested relation and collapsed one upon the other whereby the assembled springs are folded together with a wire about the same, a reciprocating carriage, a wire tying means carried thereby, said carriage being adapted to compress the springs within the baling chamber on the forward movement of the carriage and engage the wires, and means for releasing the wires on the return movement of the carriage whereby the bale is withdrawn from the baling chamber. 80
- 85 24. In a structure of the class described, the combination of a baling chamber comprising a pair of sections adapted to be opened to receive springs assembled in nested relation and collapsed one upon the other whereby the assembled springs are folded together with a wire about the same, and a wire tying means. 90
- 95 25. In a structure of the class described, the combination with means for assembling springs in nested relation of a baling chute, a wire feed means, a wire tying means, a 100
- 105
- 110
- 115
- 120
- 125

reciprocating carriage therefor adapted on its return movement to withdraw the bale from the baling chute, a bale ejector disposed at the side of the carriage, an actuating spring for said ejector, means for retracting said ejector on the forward movement of the carriage, and a holding dog for said ejector; said carriage being provided with a tappet adapted to release said dog on the return movement of the carriage.

26. In a structure of the class described, the combination with means for assembling springs in nested relation of a baling chute, a wire feed means, a wire tying means and a reciprocating carriage therefor adapted on its return movement to withdraw the bale from the baling chute.

27. In a structure of the class described, the combination with an assembling chute, means for feeding springs thereto one by one whereby they are nested therein, said feeding means including a spring "setting" means, means for ejecting the springs from said assembling chute whereby they are discharged therefrom in a nested relation in a single row, a baling means adapted to fold the single row of assembled springs upon itself into a double row, means for placing a wire around the double row of springs, and means for tying the wire.

28. In a structure of the class described, the combination with an assembling chute, means for feeding springs thereto one by one whereby they are nested therein, means for ejecting the springs from said assembling chute whereby they are discharged therefrom in a nested relation in a single row, a baling means adapted to fold the single row of assembled springs upon itself into a double row, means for placing a wire around the double row of springs, and means for tying the wire.

29. In a structure of the class described, the combination with an assembling chute, means for feeding springs thereto one by one whereby they are nested therein, said feeding means including a spring "setting" means, means for ejecting the springs from said assembling chute, and means for tying the assembled springs into bales.

30. In a structure of the class described, the combination with an assembling chute, means for feeding springs thereto one by one whereby they are nested therein, means for ejecting the springs from said assembling chute, and means for tying the assembled springs into bales.

31. In a structure of the class described, the combination with means for assembling springs in nested relation in a single row, of a baling chute comprising sections adapted to be swung to open position to receive the springs so assembled, said sections being adapted to be collapsed one upon

the other whereby the row of springs is folded upon itself, means for feeding tie wire to said baling chute when in open position whereby the wire is wrapped around the springs when the sections are folded together, and means for tying the wire.

32. In a structure of the class described, the combination of means for assembling springs in nested relation in a single row, and a baling means adapted to receive the springs so assembled in a single row and to fold the row of springs upon itself.

33. In a structure of the class described, the combination with an assembling chute, means for feeding springs thereto one by one whereby they are nested therein, said feeding means including a spring "setting" means, means for ejecting the springs from said assembling chute, and means for tying the wire.

34. In a structure of the class described, the combination with an assembling chute, means for feeding springs thereto one by one whereby they are nested therein, means for ejecting the springs from said assembling chute, means for passing a wire around the assembled springs, and means for tying the wire.

35. In a structure of the class described, the combination with an assembling chute, of means for successively feeding springs thereto comprising an oscillating member, the springs being supported under compression in said chute and frictionally engaging the walls thereof permitting the nesting of succeeding springs with preceding springs as they are fed to the chute one by one, an ejector, driving means therefor comprising a clutch, means for actuating said clutch comprising a cam, and means for actuating said cam comprising a ratchet operatively associated with said oscillating feed member whereby the ejector driving clutch is actuated when a predetermined number of springs has been delivered to the said chute.

36. In a structure of the class described, the combination with an assembling chute, of means for successively feeding springs thereto comprising an oscillating member, an ejector, driving means therefor comprising a clutch, means for actuating said clutch comprising a cam, and means for actuating said cam comprising a ratchet operatively associated with said oscillating feed member whereby the ejector driving clutch is actuated when a predetermined number of springs has been delivered to the said chute.

37. In a structure of the class described, the combination with an assembling chute, of means for successively feeding springs thereto comprising a reciprocating feed member, the springs being supported under compression in said chute and frictionally engaging the walls thereof permitting the

nesting of succeeding springs with preceding springs as they are fed to the chute one by one, an ejector, and means for controlling said ejector comprising said feed member whereby the actuation of said ejector is timed.

38. In a structure of the class described, the combination with an assembling chute, of means for successively feeding springs thereto comprising a reciprocating feed member, an ejector, and means for controlling said ejector comprising said feed member whereby the actuation of said ejector is timed.

39. In a structure of the class described, the combination of an assembling chute comprising adjustably supported opposed walls, diverging guide members in the forward ends of said walls, means for successively feeding the springs to the forward end of said chute, said feed means being adapted to engage the springs intermediate the ends thereof, said guide members being conformed to tilt the outer coils of the springs as they are delivered into the assembling chute facilitating the nesting thereof, and means for ejecting said springs in nested relation.

40. In a structure of the class described, the combination of an assembling chute comprising adjustably supported opposed walls, diverging guide members in the forward ends of said walls, means for successively feeding the springs to the forward end of said chute, said feed means being adapted to engage the springs intermediate the ends thereof, and means for ejecting said springs in nested relation.

41. In a structure of the class described, the combination of an assembling chute, diverging guide members in the forward ends of said walls, and means for successively feeding the springs to the forward end of said chute, said feed means being adapted to engage the springs intermediate the ends thereof, said guide members being conformed to tilt the outer coils of the springs as they are delivered into the assembling chute facilitating the nesting thereof.

42. In a structure of the class described, the combination of an assembling chute, diverging guide members in the forward ends of said walls, and means for successively feeding the springs to the forward end of said chute, said feed means being adapted to engage the springs intermediate the ends thereof.

43. In a structure of the class described, the combination of an assembling chute, and means for successively feeding the springs to the forward end of said chute, said feed means being adapted to engage the springs intermediate the ends thereof, the entrance to the chute being conformed to tilt the outer coils of the springs as they are delivered

into the chute facilitating the nesting 65 thereof.

44. In a structure of the class described, the combination of an assembling chute, and means for successively feeding the springs to the forward end of said chute, said feed 70 means being adapted to engage the springs intermediate the ends thereof.

45. In a structure of the class described, the combination of an assembling chute comprising top and bottom walls, the top 75 wall being longitudinally slotted, side walls adjustably supported between said top and bottom walls, said side walls being provided with pivoted guide wings at their front ends, said guide wings being adjustably supported and being provided with parts lying within the plane of the side walls whereby the outer coils of the springs are tilted as they are delivered between the side walls to facilitate nesting of the springs, means for 80 feeding the springs to said assembling chute adapted to grasp the springs intermediate the ends thereof, and means for ejecting the springs from said assembling chute comprising a conveyor provided with a flight adapted to pass through the slot of said upper wall.

46. In a structure of the class described, the combination of an assembling chute comprising top and bottom walls, the top wall 95 being longitudinally slotted, side walls adjustably supported between said top and bottom walls, means for feeding the springs to said assembling chute, and means for ejecting the springs from said assembling chute 100 comprising a conveyor provided with a flight adapted to pass through the slot of said upper wall.

47. In a structure of the class described, the combination of a swinging transfer member, a spring holder comprising a pair of pivoted arms adapted to be closed upon the ends of a spring, one of said arms being supported for lateral movement permitting it to swing out of the path of the spring delivered by said transfer member, and means for actuating said arm laterally to permit the said swinging transfer member to operate and for closing said arms together to hold a spring under compression.

48. In a structure of the class described, the combination of an assembling chute, and means for successively feeding springs to the forward end of said chute, the entrance to the chute being conformed to tilt the outer coils of the springs as they are delivered into the chute facilitating the nesting thereof.

49. In a structure of the class described, 125 the combination of a spring compressing means, a transfer member for delivering springs to said compressing means comprising jaws adapted to engage one of the end

coils of the spring, an assembling chute, and means for transferring the springs from said compressing means to said assembling chute adapted to grasp the spring intermediate its ends.

50. In a structure of the class described, the combination of a spring holder adapted to engage the ends of a spring, a transfer member for delivering springs to said holder comprising jaws adapted to engage one of the coils of a spring, and a second transfer for the springs adapted to grasp the spring intermediate its ends while supported by said holder.

51. In a structure of the class described, the combination of a spring holder and compressor comprising a pair of pivoted holder members adapted to engage the ends of a spring, the supports for said holder members being adapted to permit opening and closing movement thereof and a lateral movement of one of said holder members, a rotatable cam member provided with internal cams adapted to simultaneously swing said holder members toward each other for closing the same upon the spring, said cams being conformed to actuate the holder members to engage the spring and thereafter collapse the spring for setting the same, a cam member adapted for lifting one of said holder members to permit the positioning of a spring between the same, and a cam for swinging said holder members to open position.

52. In a structure of the class described, the combination of a transfer member, a spring holder comprising a pair of pivoted holder members adapted to engage the ends of a spring supported by said transfer member, the supports for said holder members being adapted to permit opening and closing movement thereof and a lateral movement of one of said holder members, and means adapted to simultaneously swing said holder members toward each other for closing the same upon the spring to permit the withdrawal of said transfer member to actuate the holder members and thereafter collapse the spring for "setting" the same.

53. In a structure of the class described, the combination with a spring supporting means adapted to support a spring by engagement with the ends thereof, of a pivotally mounted spring transfer arm provided with a fixed finger, a coacting pivoted finger, a spring adapted to hold said pivoted finger normally open, a cylinder on said arm, a plunger in said cylinder operatively connected to said pivoted finger, an air supply connection for said cylinder, a reciprocating control valve for said air supply adapted when in one position to admit air thereto and when in another position to exhaust air from said cylinder, means for os-

cellating said arm, a flexible connection from a fixed part of the machine to said valve whereby the valve is actuated when the arm is in its spring engaging position, and a tappet with which said valve engages when the arm is swung to its delivery position.

54. In a structure of the class described, the combination of a supporting rod, a spring transfer member comprising a pair of side plates rotatably mounted on said rod and having frictional engagement therewith, a pair of spring engaging jaws slidably mounted between said side plates, an actuating slide provided with a tapered part disposed between the inner ends of said jaws, said slide having a slot therein to receive said supporting rod and being provided with a wedge portion adapted on the forward movement of the slide to close the jaws, springs for holding said jaws normally open, an actuating cam for said transfer member provided with a cam slot, a roller on said slide engaging said cam slot, and means for actuating said cam.

55. In a structure of the class described, the combination of an assembling chute, means for successively feeding springs to the forward end of said chute, an ejector, and means for actuating said ejector operatively associated with said feed means whereby the actuation of the ejector is timed.

56. In a structure of the class described, the combination of an assembling chute, means for successively feeding springs to said chute adapted to engage the springs intermediate the ends thereof, the entrance to said feed chute being conformed so that the springs are placed under compression by the delivery of the springs thereto whereby they are frictionally retained and released by said feed means.

57. In a structure of the class described, the combination of an assembling chute, means for successively feeding springs to the chute adapted to engage the springs intermediate the ends thereof, and means associated with the chute for guiding the end coils of the springs as they are delivered to the chute to facilitate nesting thereof.

58. In a structure of the class described, the combination of an assembling chute, a reciprocating means for successively feeding the springs to the forward end of the chute adapted to engage the springs intermediate the ends thereof, and relatively fixed means for compressing the springs as they are delivered and guiding the end coils of each spring to the outside of the end coils of the preceding spring.

59. In a structure of the class described, the combination of an assembling chute, a reciprocating means for successively feeding the springs to the forward end of the

chute adapted to engage the springs intermediate the ends thereof, and relatively fixed means for guiding the end coils of each spring to the outside of the end coils of the preceding spring.

60. In a structure of the class described, the combination of an assembling chute,

means for successively feeding springs to said chute whereby they are associated in nested relation, and means for ejecting the 10 springs in assembled groups.

In witness whereof, I have hereunto set my hand.

BERT L. VAN ORMAN.
